UNITED STATES PATENT OFFICE

107,960

DESIGN FOR A COMBINED HOSE TOWER AND CABINET FOR AUTOMOBILE SERV- ICE STATIONS OR THE LIKE

Willis A. Kropp, Oak Park, Ill., assignor to
Stewart-Warner Corporation, Chicago, Ill., a
corporation of Virginia

Application April 5, 1937, Serial No. 68,564

Term of patent 3½ years

To all whom it may concern:

Be it known that I, Willis A. Kropp, a citizen
of the United States, residing at Oak Park, in
the county of Cook and State of Illinois, have
invented a new, original, and ornamental Design
for a Combined Hose Tower and Cabinet for
Automobile Service Stations or the like, of which
the following is a specification, reference being
had to the accompanying drawing, forming a
part thereof.

The figure is a perspective view of a combined
hose tower and cabinet showing my new design.
The side not shown is substantially the same as
that disclosed in the drawing.

I claim:

The ornamental design for a combined hose
tower and cabinet for automobile service sta-
tions or the like as shown and described.

WILLIS A. KROPP.
